UNITED STATES PATENT OFFICE.

MOSES OWEN, OF WESTMONT, JOHNSTOWN, PENNSYLVANIA; MARY ANN OWEN, EXECUTRIX OF SAID MOSES OWEN, DECEASED, ASSIGNOR TO HERSELF, JOHN A. NORTHWOOD, AND EMYLN HARRIS, ALL OF WESTMONT, JOHNSTOWN, PENNSYLVANIA.

CUTTING-OFF TOOL FOR BAR METALS.

1,272,508.

Specification of Letters Patent.

Patented July 16, 1918.

Application filed November 29, 1915. Serial No. 64,002.

To all whom it may concern:

Be it known that I, Moses Owen, a citizen of the United States, residing at Westmont, Johnstown, in the county of Cambria and State of Pennsylvania, have invented certain new and useful Improvements in Cutting-Off Tools for Bar Metals, of which the following is a specification.

This invention relates to multiple cutter-carrying tools for cutting off bar metals.

The objects of the invention are to improve the construction and increase the efficiency of tools of this character; to reduce danger of derangement or breakage to the minimum; to provide for ready repairs when the necessity for such arises; and to adapt the tool for rapidly cutting off bar metals of any contour in cross-section.

With the above and other objects in view, as will appear as the nature of the invention is better understood, the same consists in the novel construction and arrangement of parts of a cutting-off tool, as will be hereinafter fully described and claimed.

In the accompanying drawings forming part of this specification and in which like numerals of reference indicate corresponding parts:

Figure 1 is a face view of the tool;

Fig. 2 is a side elevation, partly in section;

Figs. 3 and 4 are detail views of one of the tool holders;

Fig. 5 is a detail view in side elevation of the head or body of the tool;

Fig. 6 is a detail view of one of the tool holder actuating screws;

Fig. 7 is a detail of one of the parts of the tool.

Referring to the drawings, the numeral 1 designates the body or head of the tool, which is a solid plate of metal of circular form, and has a portion of its periphery reduced to provide an annular guide 2, and

a circumferential flange 3. The body has a centrally disposed bore or opening 4 to receive the bar to be cut, and radiating from this opening are four lateral tubular guideways 5 disposed at right angles to each other and extending entirely through the body, each guideway being provided with a longitudinal all-through slot 6 continued throughout its length, and the outer end of each

guideway being formed with a socket or counterbore 7.

The guideways 5 and slots 6 are engaged by the nuts or heads 8 of the tool holders, and as each of these latter elements is a counterpart of the other, a description of one will serve for all. The nut or head 8 is of circular form so as to fit a guideway 5 and has extending from it, a flat neck 9 that engages the slot and carries one of the jaws 10 of the tool holder, the jaw in its outer face being provided with a channel 11 to receive the cutter C. The other jaw 12 which is secured to the jaw 10 by bolts 13, carries clamping bolts 14 which serve to secure the cutter in place. The threaded bore 15 of the nut 8 is engaged by the screw 16 of the tool holder actuator, shown in detail in Fig. 6. The intermediate portion of the actuator carries a fixed collar 17 to engage the counterbore 7, beyond which collar is a cylindrical extension 18 provided with a key-way 19 and terminating in a reduced threaded extension 20. The outer face of the collar 17 is engaged by a cap 21 having ears 22 and a central opening 23 to receive the extension 18, the opening being surrounded by a boss 24 that also engages the counterbore 7, bolts 25 engaging the ears 22, serving to secure the cap in place, and thus hold the actuator from retrograde movement.

Keyed to the extension 18 is a bevel pinion 26 which is held against danger of working loose by a washer 27 and a nut 28. Three of the actuators and pinions are identically the same, but the fourth actuator 29 is extended any desired distance beyond the body and constitutes the driving member as it receives the power from any suitable source to drive the three remaining gears and actuators. The gear 30 of the driving member 95 is additionally secured thereto by a pin 31, otherwise it is the same as the pinions 26.

Mounted to rotate upon the guide 2 and held thereon by the flange 3, is a ring gear 32 that meshes with the pinions 26 and 30 100 and imparts rotary motion thereto and thence to the tool holders, all of the latter being actuated in unison and at the same rate of speed.

In practice the head or body will be firmly 105 secured to a fixed part of a lathe or the like

and in a position best to adapt it for coöperation with the bar to be cut off.

It is to be understood that more than one cutting-off tool may be employed on one machine, and also that suitable reversing gear may be used to bring the tool holders back to the starting point, and as these additional mechanisms will be readily understood, illustration thereof is deemed unnecessary.

Having thus described my invention, what I claim is:—

1. A cutting tool comprising a stationary head having a plurality of radially disposed guideways and an annular flange, tool holders having nuts in said guideways, caps secured to the flange opposite the guideways, screws journaled in the caps and passing through the nuts, pinions carried by the screws, and a ring gear engaging the pinions to impart rotary motion to all of the pinions.

Copies of this patent may be obtained for five cents each, by addressing the "Commissioner of Patents, Washington, D. C."

2. A cutting tool comprising a stationary head having a central opening and a plurality of radially disposed guideways, an annular flange carried by the body portion and having openings communicating with the guide-ways, caps secured to the flange opposite the openings, tool holders having lateral extensions within the guide-way, and screw-threaded, screws journaled in the caps and screwed into the lateral extensions, pinions carried by the screw, a ring gear carried by the head and engaging the pinion, and means for rotating one of said screws whereby all of the screws are simultaneously rotated at the same speed.

In testimony whereof I affix my signature in presence of two witnesses.

MOSES OWEN.
